UNITED STATES PATENT OFFICE.

ERICK PETERSON, OF MINNEAPOLIS, MINNESOTA.

ORGAN OF THE REED TYPE, IMITATING PIPE TONE.

Application filed September 3, 1925. Serial No. 54,257.

This invention relates to an organ and particularly to a novel and improved structure of reed organ.

It is an object of this invention to provide a reed organ so constructed that the sharp metallic quality of tone usually produced by a reed is softened and changed to resemble a resonating pipe tone such as produced by the well known pipe organ.

10 It is a further object of the invention to provide a reed organ having a cell board or tone board having cells therein which contain a reed, there being a separate cell for each reed which is so shaped and constructed that the wind passing therethrough is so affected that the character of the tone for the individual reeds is affected and given individuality as well as producing a perfect pipe tone.

20 It is also an object of the invention to provide a reed organ having a cell board for containing the reeds, valves for controlling the inlet of air to said cells, and a chamber adjacent one side of said cell board adapted to contain air under uniform pressure.

It is another object of the invention to provide such an organ as set forth in the preceding paragraph in which a sound board is used at one side of said air chamber at 30 the side opposite the cell board, which sound board, preferably, is vertical and which has an unobstructed surface, said sound board being readily detachable and in contact with the organ only at its edge portion.

35 It is a further object of the invention to provide an organ having an upper keyboard adapted to control a plurality or series of reed cells and having a lower keyboard also adapted to control a plurality or series of reed cells, together with a manual coupler whereby the cells controlled by the upper keyboard may be connected so as to be controlled by the lower keyboard.

45 It is another object of the invention to provide an organ having a keyboard and having a series of pedals adapted to control a series of reed cells for producing certain bass notes, together with a coupler by means of which the said reed cells may be 50 connected so as to be controlled by the keyboard.

It is still further an object of the invention to provide a novel and improved structure of tremolo or vox humana attachment.

55 It is still another object of the invention to provide an air chamber for supplying air

to the tone box chamber, together with a plurality of valves for regulating the passage of air from said air chamber whereby pianissimo effects can be produced.

60 These and other objects and advantages of the invention will be more fully set forth in the following description made in connection with the accompanying drawings in which like characters refer to the same parts throughout the different views, and in which,

Fig. 1 is a vertical section taken through a 70 organ, said section being taken with a point indicated by line 1—1 on Fig. 2;

Fig. 2 is a plan view of one of the keyboards and a portion of the transport mechanism, certain parts being removed and other parts shown in horizontal section;

Fig. 3 is a partial view in vertical section 75 similar to Fig. 1, but shown on an enlarged scale;

Fig. 4 is a view in front elevation of the front side of the tone box and controlling mechanism also showing the vox humana mechanism;

Fig. 5 is a view partly in elevation and partly in vertical section showing the rear of the sound board and the air chamber above the cell board;

Fig. 6 is a horizontal section taken on the 80 line 6—6 of Fig. 5;

Fig. 7 is a view in vertical section taken on the line 7—7 of Fig. 5, shown on an enlarged scale;

Fig. 8 is a vertical section taken on the 85 line 8—8 of Fig. 7;

Fig. 9 is a view in side elevation of the valve and its operating mechanisms;

Fig. 10 is a plan view of Fig. 9, Figs. 9 and 10 being shown on a greatly enlarged 95 scale;

Fig. 11 is a view partly in plan and partly in horizontal section of the bass tone box;

Fig. 12 is a vertical section taken on the 100 line 12—12 of Fig. 11;

Fig. 13 is a vertical section taken on the line 13—13 of Fig. 12;

Fig. 14 is an enlarged view in vertical section and front elevation showing a portion of the bass coupler;

Fig. 15 is a horizontal section taken on the line 15—15 of Fig. 1;

Fig. 16 is a horizontal section of the cell board taken on the line 16—16 of Fig. 3;

Fig. 17 is a vertical section showing a

modified form of stop operating mechanism.

Referring to the drawings, particularly Fig. 1, a reed organ is illustrated, the principal parts of which may be designated as the tone or cell board and its controlling mechanism *a*, the upper keyboard *b*, the lower keyboard *c*, the transport mechanism for the keyboards, the bass cell board *e*, and a bellows *f*, with its operating mechanism. The organ will, as usual, have the frame parts 20, the baseboard or platform 21 and the lower frame parts with the usual posts 22. These parts may be, and in practice will be made quite ornamental. A horizontal supporting frame member or board 23 is provided which forms the main support for the tone cell board construction *a*. This construction includes the cell board proper *a*¹. This board extends from one side of the organ to the other and contains the reed cells *a*². The board is tapered in length as indicated in Fig. 16, in accordance with the length of the reeds used for the entire range of tones corresponding to the keys in the keyboard. The cells *a*², it will be noted, extend through the board *a*¹ in a direction normal thereto and said cells include an upper portion and a lower portion. The lower portion has an opening *a*³ at the rear of the board and the upper portion opens at the front of the board. The cells *a*² continue into members *a*⁴ which are formed as transverse bars extending across the front of the tone box and each of these bars is secured to the tone box by a comparatively small number of screws *a*⁵. It will be noted that there is a distinct portion of the cell in the member *a*⁴, which member has no reed therein and which portion forms an extension of the portion of the cell in the cell board *a*¹. By removal of the screws *a*⁵ each of these bars can be quickly and separately removed. The bars *a*⁴ form, in effect, the front side of the cell board and said cells open at the front side thereof. The reeds *a*⁶ are inserted in grooves formed in the cell board and it will be noted that these reeds are disposed between the upper and lower portions of the cells *a*². The cells *a*² may, in other words, be said to have an intermediate enlarged portion across which the reeds transversely extend. The cross sectional shape of the cells and their ends are shown in Fig. 8. In said figure it will be noted that one side of the cells, shown as the top side, has surfaces disposed at an angle to each other, which surfaces converge and meet at the central point in the cell to form a point in vertical cross section. The various shapes of these cells give various characters to the tones produced by the reeds therein. It will also be noted that at the front of the cells or at the front of the portion in the members *a*⁴ there

is a downwardly projecting lip *a*⁷ having a comparatively sharp lower edge and an upwardly inclined inner surface. This lip also gives a modulation and distinct character to the tone produced in the cell. A large number of vertically spaced rows of these cells are provided, ten rows being shown in the cell board *a*. The rear openings *a*³ of the cells are the air inlet openings and it will be noted that adjacent cells in the cell board are of reverse shape so that the openings *a*³ are formed in closely adjacent pairs. Each pair of these openings is controlled by a valve *a*⁸ (see Figs. 1, 3, 7, 9 and 10). While the valves *a*⁸ may be variously formed, in the embodiment of the invention illustrated, they are shown as a narrow somewhat rectangular piece with tapered upper ends and are provided on their front or seat portion with layers of felt *a*⁹. The valves *a*⁸ are secured by metal clips *a*¹⁰ to the upper end of the carrying bars *a*¹², as clearly shown in Figs. 9 and 10, the clips *a*¹⁰ being secured to the converging sides of the valves *a*⁸ by small tacks. The bar *a*¹² has pivot pins *a*¹³ projecting at each side which are pivoted in slots formed in bars *a*¹⁴ secured to and extending across the rear side of the cell board or tone box proper *a*¹. The pins are held in place by small bars *a*¹⁵ overlying the bars *a*¹⁴. Each bar *a*¹² has a small bracket *a*¹⁶ projecting therefrom adjacent its lower end and secured thereto by suitable small tacks or screws and each bar is contacted adjacent its upper end by the lower end of a spring *a*¹⁷ having an intermediate loop therein and secured at its other end to the rear side of the cell board *a*¹, the free end of the spring being disposed in a small groove *a*¹⁸ formed in the rear of bar *a*¹². A headed pin *a*¹⁹ extends through a hole formed in bar *a*¹² and carries a felt washer *a*²⁰, said pin being provided to prevent turning or twisting of valve *a*⁸ and being secured therein. Headed stop pins *a*²¹ having felt washers *a*²² therein also project through slots in the upper ends of valves *a*⁸, being secured in cell board *a*¹. The two upper rows of valves *a*⁸, and the four upper rows of cells *a*² controlled thereby are operated or controlled from the upper keyboard *b* of the organ. The brackets *a*¹⁶ in the upper row of valves have a small wire or rod *a*²¹ extending therethrough onto which is threaded a small leather plug *a*²² beneath which and between which and the upper side of the bracket is a small felt washer *a*²³. The rod *a*²¹ also extends through the bracket *a*¹⁶ in the row directly therebeneath and is threaded at its lower end to receive a similar leather plug *a*²² between which and the lower side of the brackets is another felt washer *a*²³. Another rod *a*²¹ also extends through the brackets *a*¹⁶ of the valve in the second row of valves from the top and the upper end

of this rod is also threaded to receive one of the leather plugs a^{22} beneath which is disposed one of the felt washers a^{23} . The rod a^{24} extends downwardly at the rear of the cell board and it will be understood that there is one of these rods for each one of the cells in a row extending across the cell board. The wires or rods a^{24} are connected at their lower ends to the transport mechanism 5 operated by the upper keyboard in a manner to be later described. The three rows of valves a^8 and the bars a^{12} controlling the cells in the lower rows of cells in cell board a^1 are, as stated, controlled by 10 the lower keyboard c , and for this purpose, small rods or wires a^{25} extend through the brackets a^{16} on said bars a^{12} , which bars a^{25} are thus three in number and are in all respects similar to the rods a^{21} , already described, and have thereon the leather plugs a^{22} and the felt washers a^{23} . The lowermost bracket a^{16} is connected to a wire a^{26} similar to the rod a^{24} and having thereon the same kind of leather plug a^{22} and washer a^{23} . 15 There is also one of the rods a^{26} for each cell in a row extending across the cell board and said rods a^{26} extend downward and are connected to the transport mechanism operated by the lower keyboard c in a manner to be 20 later described.

The front openings of the cells a^2 are closed by the valves a^{27} (see Figs. 1, 4, 7 and 8). The valves a^{27} are formed as comparatively long bars having layers of felt a^{28} on their inner surfaces which form the seats. 25 As shown in Fig. 4, the valves a^{27} are made in three sections, which sections are separately connected by the hinges a^{29} to the lower sides of the bars a^4 . The sections of the valves a^{27} at the right of Fig. 4 are adapted 30 to be operated in unison and for this purpose a plate aa is secured to the central sections and overlaps the upper beveled side of the sections at the right of Fig. 4. Each of 35 the sections of the valves a^{27} normally are held in closed position by a torsion spring a^{30} engaging the lower beveled surface of the valve sections at one end and secured to the bars a^4 at its other end. The sections and 40 valves a^{27} , at the left, as shown in Fig. 4, extend over the cells forming the bass notes or those on the bass clef, while the bars or 45 sections at the right, as shown in Fig. 4, extend over the cells forming the treble notes or the notes on the treble clef. The 50 valves a^{27} at the left, as shown in Fig. 4, which will be called the bass valves, and the sections of valves a^{27} at the right of Fig. 4, which will be called the treble valves, are 55 each operated by a crank rod a^{30} journaled in the vertical side bars or boards a^{31} . The inner end of the crank rod has an arm a^{32} adapted to engage the inner surface of the 60 valve section so that when said crank rod 65 is revolved the valve will be swung open about its hinge a^{28} . The various valve sections a^{27} are operated to give the different characters of organ tones and for this purpose the crank rods a^{30} are connected by wires a^{33} to the crank arms on the outer end 70 of crank rods a^{34} suitably journaled in small clips a^{35} secured to a vertical board or plate a^{36} shown as engaging the front edge of board 23. Links a^{37} also connect various pairs of the crank rods a^{34} . The crank rods a^{34} are each provided with a crank portion a^{37} , to each of which is pivotally connected a rod a^{38} . The rods a^{38} extend upwardly in and are guided in a horizontal board or plate a^{39} extending outwardly adjacent the 80 top of plate or board a^{36} . It will be seen that when one of the rods a^{38} is depressed one of the bass valve sections a^{27} will be opened or a pair of the treble valves a^{27} will be opened. The pins a^{38} are depressed by 85 levers a^{40} pivoted in the frame portion a^{24} of the organ frame at the front thereof, which levers have a layer of felt a^{41} on their lower sides adapted to engage the top of pins a^{38} . The levers a^{40} have a cam projection a^{42} at their inner ends which is raised by the inclined surface of a cam projection a^{43} extending upwardly at the inner end of stop rods a^{44} , which stop rods have the stop knobs a^{45} at their outer ends and are 90 guided in the frame 24. These stops determine certain characters of organ tones and, as shown, there are twenty-four of these stops which are provided with designations 95 as follows:

"Pianissimo, Diapason, Pedal coupler, Echo, Viola, Clarion, Gamba, Clarinet, Vox jubilante, Flute, Aeolian harp, Vox humana, Agitato, Harp celeste, Salicional, Trumpet, Cello, Harp ophicleide, Flute harmonique, 105 Vox celeste, Treble coupler, Piano, Melodia."

There will also be a plurality of stops (not shown) at each end of the stops a^{45} and below the same.

Each of the wires a^{33} connected to the 110 crank arms on the outer end of crank rods a^{34} extends downwardly below said crank arms and is formed with a vertically extending loop a^{30} . Bail members a^{46} are journaled in blocks a^{32} and have their upper and 115 forward ends a^{47} extending through the loops a^{30} . Each bail member is engaged at its upper and forward end by the notches in the lower ends of bars a^{31} , which bars 120 converge toward their upper ends and are connected to a link (not shown), extending 125 downwardly to a suitable crank shaft which will be operated by a depressing mechanism preferably a foot pedal. This pedal will also be connected to all of the valves a^{16} so that all notes will be played when this pedal is operated. This pedal, with the coupling mechanism in operation, will give the full organ tone.

The reeds used are the ordinary commer-

cial metal reeds comprising the vibrating tongue secured on a metal plate, as clearly illustrated in the reeds a^5 shewn in Fig. 11. It may be stated that these reeds are 5 made in three widths referred to as normal, undersize and oversize, and further are designated as giving a tone equivalent to a certain length of organ pipe, such as 2, 4, 8 and 16 feet. While the reeds used 10 depend considerably on the tones desired, it may be stated that in one embodiment of the present invention, the reeds used in the upper two rows of the cells a^2 in the cell board a^1 in the treble section thereof, are 15 undersized 8 ft. reeds. In the third row from the top, 4 ft. normal reeds are used. In the 4th row, 8 ft. oversized reeds are used. In the 5th row, 4 ft. normal reeds are used. In the 6th row, 8 ft. undersized reeds are 20 used. In the 7th row, 4 ft. normal and in the 8th row 8 ft. normal reeds are used. In the 9th row 16 ft. oversized reeds are used and in the lower or 10th row, 8 ft. oversized 25 reeds are used.

25 In the bass section, in the first and second or top two rows, 2 ft. undersized reeds are used. In the third row, 4 ft. normal reeds are used and in the fourth row 8 ft. oversized reeds are used. In the fifth and sixth 30 rows, 2 ft. and 4 ft. normal reeds are, respectively, used. In the seventh and eighth rows 4 ft. undersized and 8 ft. normal reeds, respectively, are used. In the ninth and tenth rows, 16 ft. oversize and 8 ft. oversize 35 are, respectively, used.

35 A plate or board a^6 is disposed at the top of cell board a^1 and projects over the top rear portion thereof having a downwardly directed vertical portion a^{57} .

40 Spaced some distance from the front of the cell or tone board and disposed in a substantially vertical position are the registers a^{46} . The registers a^{46} comprise two 45 panels having felt strips a^{47} at their inner edge surfaces which fit against the frame or casing of the organ extending about the rear of the cell board, which casing is comprised by the top plate or board 25, the inner vertical plates or boards a^{51} and the bottom plate a^{59} . One of the panels a^{46} fits on the 50 said frame or casing at the left, as seen in Fig. 4, and is of sufficient width to cover the bass valves and is substantially the same width as the length of the bass valves a^{27} . The other panel a^{46} at the right fits against the panel a^{46} at the left and extends over the treble valve sections a^{27} . The panels a^{46} have holes in their bottom portion or bar 55 which fit over pins a^{48} projecting upwardly from member a^{29} . The panels are placed over these pins and then pressed against the rear edges of member 25, a^{51} and held in place by hooks a^{49} engaging in eyelets a^{50} at the top of said panels. The registers can 60 thus be removed almost instantly by merely

releasing the hooks a^{49} and when they are so removed the rear of the cell board a is revealed and accessible and appears as seen in Fig. 4. The registers a^{46} comprise a series of horizontal pivot slats or shutters a^{51} pivoted at their ends in the sides of panels a^{48} and the shutters have an angle bracket a^{52} projecting from its rear side substantially midway between its ends, the outer 65 end of which is apertured to receive the upper hooked end of a two-arm spring a^{53} having a loop at its angle portion between its arms. The other end of spring a^{53} is secured to the shutter a^{51} directly below the bracket a^{52} on the superposed shutter. 70 The shutters a^{51} are thus held in closed position and kept from warping outwardly by the springs a^{53} , it being understood that there is no spring on the top shutter and no bracket a^{52} on the lowermost shutter. The 75 register shutters a^{51} are normally spring pressed to closed position but must be open when the organ is played and these shutters are opened by links a^{54} connected to arms a^{55} secured to the shutters a^{51} adjacent their 80 ends. The links a^{54} are connected to a link a^{56} which is controlled and pulled upon to open the shutters a^{51} and by a knee swell or knee-operated levers at the front of the organ. It will be understood that there will 85 be a link a^{54} in the right hand register panel as seen from the front of the organ and this link will be controlled by the right hand knee swell or lever. The knee swells or levers are arranged with spring-pressed pawls 90 adapted to move over a ratchet so that they will be held in any position to which they are moved. The pawls are readily released by stops or handles thereon adapted 95 to be engaged by the knee and the knee swells or levers are moved toward each other to normal position and the register shutters a^{51} closed by springs a^{53} . The door ee^2 is 100 opened by a link e^{55} secured to the top thereof which will be connected for operation to one of the stops at the ends of the stops a^{45} on panel 24.

105 The wires a^{24} and a^{26} extend through a slot formed in the bottom of board or plate 23 and through covering 23^a thereon make a tight fit so that a substantially air-tight structure is formed. A plate 25 extends across the top of the cell board and has a 110 series of openings 24^a and 24^b therethrough through which air passes. There is a chamber formed at the rear of the cell board a^1 , the rear side of which is formed by a vertical sounding board 26. The sounding board 26 is provided with a projecting rim 26^a 115 which fits against the corresponding rim or surface at the rear of the frame of the organ or the door of the chamber in the rear of said cell board, as shown in Figs. 1 and 5. The sounding board 26 is provided with 120 a pair of handles 26^b on its rear side and has 125

130

spaced vertical strips 26^a at its rear side. The side and top and bottom edge portions of the sounding board have secured thereto the plates 27 having open slots in their outer ends. These slots are adapted to receive swinging bolts 28 pivoted in small clips 29 secured to the rear of the organ frame, which bolts are threaded to receive wing nuts 30 engaging washers 31 therebeneath, which washers engage the outer sides of plates 27. Springs 27^a above board 26 swing bolts 28 upwardly when released. By swinging the bolts 28 into the slots in plates 27 and tightening the wing nuts 30, the sounding board 26 can be quickly secured in place, and by loosening the nuts 30 and swinging outwardly, the bolts 28, the sounding board can be very quickly removed and access had to the rear of the cell board. It will be noted that the inner surface of the sounding board 26 is entirely smooth, unobstructed and unpierced by any fastening or securing means whatever, and also that the outer surface of the board is substantially unobstructed having thereon only the strips 26^a and handles 26^b. There is an air chamber 32 formed above the plate or board 25 which is shown as of box or rectangular form, into which chamber the openings 24^a and 24^b extend. The chamber is divided by an intermediate partition 32^a and has another partition 32^b at one end thereof, being shown at the left hand in Figs. 5 and 6. Vertical channels 32^c extend downward at each side of the organ from the ends of chamber 32 for a purpose to be later described. The openings 24^b at one side of partition 32^a are controlled by a valve in the shape of an elongated bar 33 hinged to the bottom of said casing by hinges 34. This valve is normally open but may be closed by means of the crank rod 34 suitably journaled in small brackets 35 on the top of plate 25 and having an arm at one end connected by a link 36^a to the top of valve 33. The other end of crank rod 34 has an arm connected to a link 37, which link 37 extends downwardly and is connected to one of the crank rods 30^a which is operated by a suitable stop 35. The openings 24^a at both sides of partition 30^b are adapted to be controlled by valves 38 similar to the valve 33 and hinged to the bottom of chamber 32 by the hinges 39. The valves 38 are normally opened but may be closed by means of a crank rod 40 journaled in suitable brackets 41 secured to the bottom of the chamber 32, the crank portions of which are connected by links 42 to the valves 38. One crank portion of the crank rods 40 is also connected by a link 43 to the arm at one end of a crank rod 44 journaled in bracket 45 secured to the top of plate or board 25 and having an end arm connected by a link 46, which link extends downwardly and is connected to one of the crank rods 30^a and operated by a suitable stop 35. It may be stated that the stops connected to links or wires 37 and 46 are connected to pianissimo stops (not shown), which are disposed below the stops 70 75 at each end thereof and are similarly operated. It will be noted that a link 47 connects valve 33 and the valve 38 at the right of Fig. 6, which link has a slot 47^a therein engaging a screw in the top of said valve 38. When valve 33 is operated by its link 36 the valve 38, at the right of Fig. 6, also will be operated. It will also be noted that, owing to the slot in the link 42 at the right hand end of crank rod 40, that when valve 38 at 80 the right is thus operated it will not operate crank rod 40, the screw in the top of said valve 38 merely moving in the slot in the link 42. It will also be noted that when valve 38 shown at the right in Fig. 6 is operated from crank rod 40 it will not operate valve 33, the screw in the top of said valve 38 merely moving in the slot in link 47. A valve 48 controls an opening in partition 32^b and is pressed to closed position by a spring 85 90 95 49. Whenever valve 38 at the right of Fig. 6 is open, however, valve 48 is cammed open by the right angle rod 50 secured to the top of said valve 38. There is also a valve 51 closing an opening through partition 32^a, 95 which valve has a coiled spiral spring 52 of comparatively thin material secured thereto. Valve 51 is swung open by the crank shaft 40, which extends beneath its free edge, 100 whenever valves 38 are open.

A casing 53 surrounds the casing surrounding chamber 32 forming a chamber 54. Adjacent the casing 53 is a comparatively narrow rectangular casing 55 having a central chamber therein in which is journaled a turbine wheel 56 having a multiplicity of radial vanes 56^a and side portions 56^b at the sides of said plates. A passage 54^a extends from the chamber 54 into the chamber of casing 55 being substantially tangential to 110 said latter chamber and adapted to direct an air current against the vanes 56^a. The casing 55 also has an outlet opening 55^a leading from the chamber therein. The opening 54^a is controlled by a valve 57, 115 which is pivoted in brackets 58 secured to the inner side of casing 53, said valve having an operating arm 57^a secured thereto to which is connected a link 57^b, the other end of said link being connected to a crank 120 arm formed in one end of a crank rod 59, (see Fig. 4) which crank rod is journaled in brackets 45 on the top of plate 25 and also in brackets 45^a on top of plate 25. The turbine 56 is mounted on a shaft 60 journaled in casing 55 and in a bearing 61 upstanding from a plate resting on top of the casing surrounding chamber 32. Shaft 60 carries at one side of the casing 55^a, a fan 125 130 62 shown as having oppositely disposed

blades and said shaft has a small pulley or cylindrical portion 60^a adjacent one side of casing 55. An arm 63 is journaled at one end on a pin projecting from casing 55 and has an end surface of frictional material 63^a adapted to swing by and engage the surface of member 60^a. The arm 63 is connected by a link 64 to a crank portion 59^a on crank rod 59. The end of crank rod 59 opposite link 51^b is provided with an arm to which is connected a link 65 which is connected to one of the crank rods 20^a and will be operated by a stop disposed at the front of frame 24 of the organ. This stop will be designated "Vox humana" and the parts designated 54 and 65 form the vox humana or tremolo attachment.

The bass cell box *e* is disposed in a casing *ee* adjacent the bottom of the organ (see Figs. 1, 11, 12 and 13). The casing *ee* has therein a cell board proper *e*¹ in which are formed rows of cells *e*². The cells *e*² are open at their upper ends into the chamber *e*⁴ and have front openings at the front of the cell board *e*¹ and also have the reeds *e*³ extending thereacross. The upper openings of the cells *e*² are controlled by the valves *e*⁵ spring pressed to closed position by the springs *e*^{6a} and engaged at their front ends to be opened by lugs or collars *e*⁷ on vertically movable rods *e*⁷ guided in casing *ee* and in the bar *e*⁸ secured to cell board *e*¹. The rods *e*⁷ have pins *e*^{7a} also guided in a slot in the bar *e*⁸ to prevent turning of said pins and said rods are also provided with stop collars *e*^{7b} adapted to engage the bottom of casing *ee*. The valves *e*⁵ are pivoted at their front ends on the pins *e*^{5a} and are guided in their lifting movement by slots at their rear ends in which are disposed the pins *e*^{5b}. The rods *e*⁷ are adapted to be engaged at the lower ends by the inner ends of pedals *e*⁹ having felt pads *e*¹⁰ thereon with which said pins contact. The pedals *e*⁹ are pivoted adjacent their centers on a bar *e*¹¹ secured to the bottom 21 and said pedals normally rest at their front ends on pads secured to a bar *e*¹². The pedals *e*⁹ are pivoted by having slots *e*^{9a} at their centers in which pins *e*¹³ extend, which pins are fastened in bar *e*¹¹. The front ends of the pedals are guided by slots *e*^{9b} through which extend pins *e*¹⁴ secured to and projecting upwardly from a bar *e*¹⁵ padded on its upper surface. The rods *e*⁷ are quite close together and in order to space the pedals for efficient operation at the front portion thereof, said pedals are arranged in diverging relation toward their front ends, as shown in Fig. 11. The openings at the front of the cells *e*² are controlled by the valves *e*¹⁶ hinged to the bottom of casing *ee* and a board or plate *e*¹⁸ by hinges *e*¹⁷. The valves *e*¹⁶ are formed as bars extending over one row of openings from cells *e*² and these valves are operated by crank rods *e*¹⁹ journaled adjacent the bottom of casing *ee* and plate *e*¹⁸ and extend in one end of casing *ee* where they are provided with crank arms *e*²⁰. The crank arms *e*²⁰ are adapted to be operated by links (not shown) extending vertically and adapted to be lifted by stops on frame 24 similar to the stops *a*⁴⁵, which stops also are not shown. The casing *ee* has a hinged door *ee*² at its top and front portion by means of which access may be had into said casing, and forming a swell for tone board *e*¹.

There is a tremolo or vox humana attachment disposed on top of the casing *ee*, as shown in Fig. 15, which attachment is a substantial duplicate of that used above chamber 32, and comprises a fan *e*⁵⁰ carried on a shaft journaled in a suitable bracket *e*⁵¹ mounted on casing *ee* and in a casing *e*⁵² mounted on casing *ee*. The casing *e*⁵² contains a turbine similar in all respects to the turbine 53, already described, and the shaft carrying fan *e*⁵⁰ is also provided with a starting lever *e*⁵³ similar to lever 63. The turbine in casing *e*⁵² is operated by air supplied from casing *ee* and casing *e*⁵² is connected to casing *ee* by a valve-controlled opening, the valve therefor being operated through a suitable connecting link by a small lever (not shown), at the front of one of the keyboards.

The air for the reed cells *a*² and *e*² is supplied from a chamber *f*¹ in the form of a bellows chamber having the movable side *f*² pivotally mounted at one end and connected by the folding end and bottom walls *f*³ to the fixed side *f*⁴. The movable wall *f*² is contacted by a plurality of diverging and connected pairs of leaf springs *f*⁵, one end of each spring of said pairs engaging the outer side of movable wall *f*² adjacent its lower end and the other leaf of each pair engaging the rear wall 21^a of the organ. The wall *f*² is provided with a resilient flap valve *f*⁶ connected to wall *f*⁴ by a flexible member or cord *f*⁷ so that if wall *f*² is sufficiently moved, said valve will be opened.

The wall *f*⁴ is provided with a plurality of openings *f*^{4a} which are normally closed by the resilient flap valves *f*⁸ and air is forced into the chamber *f*¹ by a pair of bellows *f*⁹ having the movable wall *f*¹⁰ and the folding end and bottom wall sections *f*^{10b}. The wall *f*¹⁰ is provided with openings *f*¹¹ covered at the inner side by the resilient flap valves *f*¹². The bellows *f*⁹ each have connected to the movable wall *f*¹⁰ thereof, at its top, a strap *f*¹³ running over pulleys *f*¹⁴, said straps extending vertically from said pulleys and being connected to the ends of a vertically oscillatory bar *f*¹⁴ pivoted at its center on the headed and nutted bolt *f*¹⁵ whereby, by reciprocation of the bar *f*¹⁴ the straps *f*¹³ will alternately be pulled upon and bellows *f*⁹ operated. The inner side of the chamber

f¹ and of bellows f⁹ preferably is lined with bellows cloth which is glued to light boards forming the walls f², f⁴ and f¹⁰. These boards are reinforced by strips at their outer sides extending at an angle to each other. The folding walls f³ and f^{9b} are connected by strong reinforced bellows cloth f¹⁶ and, as shown, said walls and the adjacent walls are beveled so that the bellows can be closely collapsed. The air in chamber f¹ passes through the opening f¹⁷ at the ends of said chamber into the vertical passages 32^a already described and which are located at each side of the organ and from these passages into the chamber 32. The air also passes from the vertical passages 32^a (see Fig. 15) into chambers in casing f¹⁸ disposed above casing ee and conduits f¹⁹ lead from casing f¹⁸ downwardly into the casing ee.

As stated, the valves a⁸ in the cell board a are adapted to be operated from an upper keyboard b and lower keyboard c. The lower keyboard is shown in plan in Fig. 2. See also Figs. 1 and 3. This board comprises the usual white keys c¹ and the black keys c², which latter keys, as usual, are for the sharps and flats. The keys c¹ and c² are formed as levers having horizontal slots at their rear ends engaging a projection on the molding c³, said rear end of said key levers resting on a felt piece c⁴ formed on a projection or rest extending from molding c³. The key levers also have a vertical slot therethrough extending over a pin c⁵ projecting upwardly from the lower projection of molding c³. The key levers also have vertical slots in their undersides extending respectively over pins c⁶ disposed adjacent the forward ends of the key levers which upstand from a bar c⁷, which bar is also overlaid with felt onto which the key is depressed. The key levers c¹ and c² each extends over a pin c⁸ disposed just in the rear of its longitudinal center, which pin upstands from a lever c⁹ having a slotted forward end engaging the top lip or flange of a channel molding c¹⁰, the end of lever c⁹ resting on a felt strip in the channel of molding c¹⁰ and having a vertical slot in its forward end embracing a pin c¹¹ upstanding from molding c¹⁰. The lever c⁹ has a felt pad on which the pin c⁸ rests and said lever is rotated at its forward end to embrace a pin c¹² upstanding from the forward end of a lever c¹³ having a felt pad on its forward end on which the rear end of lever c⁹ rests. Lever c¹³ is pivoted substantially at its center on a pin c¹⁴ upstanding from the bar c¹⁵ having a felt pad on which lever c¹³ rocks and the forward end of lever c¹³ is adapted to rest on a felt pad on a block c¹⁶, said bars or blocks c¹⁵ and c¹⁶ resting on an intermediate board or platform c¹⁷ of the organ which supports the transport mechanism. The rear upper surface of lever c¹³ carries a pad on which rests the forward end of a lever c¹⁸ and lever c¹⁸ has a pin c¹⁹ projecting upward from its rear end which is engaged by a vertical slot in the forward end of lever c¹⁸. Lever c¹⁸ is pivoted substantially at its longitudinal center on a pin c²⁰ extending between vertically spaced blocks c²¹, the lower of which is carried on the platform c¹⁷ and the rear end of lever c¹⁸ is provided with a vertical slot embracing the lower end of the link a²² which has one of the leather plugs a²³ threaded on its lower end surmounted by one of the washers a²⁴ on which the rear end of lever c¹⁸ rests.

The upper keyboard comprises the same number of keys as the lower keyboard, which include the white keys b¹ and the usual black keys b². These keys are each formed as a lever having a horizontal slot at its rear end embracing a projecting lip on the molding b³ having a horizontal ledge or projection at its lower end carrying a felt pad disposed beneath the rear end of the keys b¹ or b². Said key levers b¹ and b² each have a vertical slot at their rear ends embracing a pin b⁴ upstanding from a ledge on molding b³. The keys b¹ and b² have vertical slots in their lower sides each embracing a pin b⁵ upstanding from the top of a rabbeted molding or bar b⁶ which is overlaid by a felt strip onto which the keys b¹ and b² are depressed. The keys b¹ and b² carry, respectively, pins b⁸ which are disposed slightly in the rear of their longitudinal centers and which pins engage a felt pad carried between the ends of a lever b⁹ disposed at its forward end in a rabbet in bar b⁷ and having a vertical slot embracing a pin b¹⁰ traversing said rabbet. The rear end of lever b⁹ has a felt pad on its undersurface engaging a pin b¹¹ vertically movable in and guided in a channel board or molding b¹². The lower end of said pin rests on the felt pad on top of the rear end of a lever b¹³, the forward end of which lever is received in a channel molding b¹⁴ and has a vertical slot embracing a pin b¹⁵ extending across the channel in bar b¹⁴. The rear end of lever b¹³ carries a felt pad which rests on the forward end of a lever b¹⁶ pivoted intermediate its ends on a pin b¹⁷ upstanding from a bar b¹⁸ supported from platform c¹⁷. The lever b¹⁶ has a pad on its top at its rear end on which rests the forward end of another lever b¹⁹, said lever b¹⁶ having a headed pin b²⁰ secured therein and braced by a slot in the forward end of lever b¹⁹, said pin b²⁰ having a felt washer b²¹ above the lever b¹⁹. The lever b¹⁹ is pivoted substantially midway of its ends between the blocks b²² supported from the platform c¹⁷ and the rear end of this lever is provided with a vertical slot embracing the

link a^{24} already described, said link having one of the leather blocks a^{22} threaded thereon and surmounted by a felt washer a^{23} on which the rear end of lever b^{19} rests. It may be here stated that the frame 24 carrying the stop operating mechanism is provided with slots 24^a and 24^b at its top and bottom, respectively, which engage pins 24^c projecting inwardly from the sides of the organ frame so that the frame portion 24 can be tilted and readily removed. The panel 24^d rests on frame 24 and is merely ornamental and is also readily removable.

Attention is called to the fact that the members b^3 and b^7 are secured to end boards or plates b^{22} and these plates are hinged by the hinges b^{21} to the lower end boards or plates b^{23} . With this construction, when frame 24 is removed, the upper keyboard 23 with the levers b^9 can be lifted upwardly as a unit about the hinge b^{21} thus exposing the rear end of the lower keyboard a . It is also pointed out that the frame pieces or boards b^{25} are hinged at the forward ends by the hinges c^{22} to frame members or end boards c^{23} . The frame members b^{25} carry the bars b^{12} , c^4 and c^7 so that they can be swung upwardly about hinges c^{22} , together with the members b^{23} after frame 24 is removed so that both keyboards then swing as a unit and the transport mechanism beneath the lower keyboard is thus exposed. The frame members c^{23} are further hinged by the hinges c^{24} to the base or platform c^{27} and can also be swung upwardly about said hinges. The keyboard and transport mechanism at the front of the organ is, therefore, constructed in separate units which can be successively lifted upwardly and all parts of the mechanism thus exposed so that any adjustment or repairs can be made without the necessity of disassembling the structure by removal of screws or bolts.

The organ is provided with various coupling mechanisms comprising a manual coupler for coupling the upper keyboard to the lower keyboard, a bass and treble coupler and also with a coupling mechanism for coupling the pedal-operated bass tone board to the lower keyboard. The manual coupler comprises a plate or board c^{25} supported in frame b^{25} and extending between the ends thereof. Plate c^{25} is pivotally mounted by hinges c^{28} secured to its rear lower side and also secured to the channel bar b^{12} which is rigidly carried by members b^{25} . This plate has journaled thereon in the strips c^{29} a multiplicity of crank rods c^{31} , (see Figs. 2 and 3). The crank rods are bent in the rear of the rear strip c^{29} , as shown in Fig. 2, and provided with flat rear portions overlying collars b^{27} rigidly carried on pins b^{11} . The front ends of crank rods c^{31} are also bent laterally, as shown in Fig. 2, and then provided with front flat end portions which

align, respectively, with the keys c^1 and c^2 and also with adjustable blocks c^{30} depending from the underside of keys c^1 and c^2 and having felt pads on their lower surfaces. The front ends of crank rods c^{31} normally 70 are not contacted by the blocks c^{30} but plates c^{32} can be raised by crank rods c^{31} having crank portions underlying its front edge at its ends, which crank rods are journaled in the frame members c^{23} and have crank arms 75 disposed outward of said members which are connected to links c^{32} . The links c^{32} are connected by appropriate links to lever connections (not shown) to stops similar to the stops a^{45} , which stops will be designated 80 "Manual coupler."

The bass coupler comprises a plate or board c^{33} connected by hinges c^{34} to a bar c^{35} carried on a plate c^{36} secured by bracket c^{37} to the frame member c^{23} . The plate c^{33} has journaled thereon a plurality of crank rods c^{38} held in the clips c^{39} , which crank rods have rear flat portions adapted to overlie the tops of collars c^{40} rigidly carried on pins c^8 which are operated by 90 the twelve keys at the left of the lower keyboard. The crank rods c^{38} have forward reversely bent portions having flat terminals which are disposed, respectively, beneath adjustable blocks c^{41} depending from the second group of twelve keys taken from the left hand end of the keyboard c , as shown in Fig. 2. Blocks c^{41} have felt pads on their lower edges adapted to engage the forward terminals of crank rods 100 c^{38} normally are too low to be engaged by the blocks c^{41} but plate 33 is adapted to be raised so that said terminals may be engaged by blocks c^{41} , and for this purpose a crank rod c^{42} , shown at the left in Fig. 2, is journaled in frame member c^{23} . The crank rod c^{42} has a link c^{43} secured to its outer arms outside of frame c^{23} , which link c^{43} will be connected to one of the stops 105 disposed in frame 24, which stop will be designated "Bass coupler."

The treble coupler comprises a board or plate c^{44} hinged by hinges c^{45} to the bar c^{35} , which plate has journaled thereon in the clip c^{46} a plurality of crank rods c^{47} . The crank rods c^{47} are bent at their rear ends, as shown in Fig. 2, and provided with rear flat terminals adapted to overlie collars c^{48} carried on the pins c^8 which are operated by the pins c^8 which are operated by the first twenty-five keys c^1 and c^2 from the right of keyboard, as shown in Fig. 2. The crank rods c^{47} are reversely bent at their forward ends and provided with flat terminal portions, as 120 shown in Fig. 2, which terminal portions are adapted to underlie adjustable blocks c^{49} depending from the underside of the keys c^1 and c^2 which are the 13th to the 125 37th keys, inclusive, from the right hand 130

end of the keyboard, as shown in Fig. 2. The plate e^{44} is also normally too low for the forward terminals of the crank rod e^{47} to be engaged by the blocks e^{41} but said plate can be raised by a crank rod 49 also journalled in members c^{23} and having a crank portion underlying the front edge of plate c^{44} . Crank rod e^{19} has an arm outside of crank c^{23} connected to a link e^{50} , which link e^{50} will also be suitably connected to a stop similar to stop a^{46} which will be designated "Treble coupler."

The bass notes operated by the pedal e^9 , already described, may also be operated by the lower keyboard and for this purpose, a plurality of crank rods e^{26} are provided journalled in clips e^{27} secured to a vertical board or plate e^{28} extending between the frame members 22 of the organ beneath platform c^{17} . The crank rods e^{26} are also held in place by the plates e^{29} overlying the same which are also fastened to plate e^{28} . The crank rods e^{26} , as shown in Fig. 14, are of varying lengths and are disposed in two groups which have their outer ends, respectively, directed to the right and left hand sides of plate e^{28} , as seen from the front of the organ. The inner ends of crank rods e^{26} are bent outwardly and provided with perforated terminals e^{30} into which terminals, respectively, extend the pins e^{31} projecting from the points of vertical rods e^{32} , felt washers e^{33} being disposed between the said terminals and the lower ends of rod e^{32} . The rods e^{32} extend upwardly through and are guided in the board of platform c^{17} . A lever e^{34} overlies each of the rods e^{32} and has a downwardly extending cam portion e^{35} at its rear end. The rear end of lever e^{34} is received in a rabbit in a bar e^{36} , said lever having a vertical slot embracing a pin e^{37} upstanding from bar e^{36} . The lever e^9 , already described, has a pin e^{38} projecting downwardly from its undersurface adjacent its rear end, which overlies the lever e^{34} . The bar e^{36} and levers e^{34} are adapted to be moved rearwardly on platform c^{17} and for this purpose a crank rod e^{39} is journalled in the side of the organ frame beneath hinged portion c^{23} adapted to be swung to move said bar and levers e^{34} rearwardly. The crank rod e^{39} will be operated by a crank arm at the side of the organ frame, which will be connected by suitable link mechanism to a stop on frame 24 similar to stop a^{45} , which stop will be designated "Pedal coupler." The outer ends of crank rods e^{26} are disposed in spaced relation and spaced much farther apart than pins e^{32} , as shown in Fig. 14. These outer ends are also provided with perforated terminals e^{40} through which project pins e^{41} extending from the upper ends of rods e^{42} , a felt washer e^{43} being disposed between

said terminals and the upper end of each rod. The rods e^{42} extend downwardly in front of casing ee and have projecting pins e^{44} at their lower ends received in holes in the pedals e^9 , a felt washer preferably being disposed between each pedal and its rod e^{42} .

In Fig. 17, a modified form of stop operating mechanism is shown. With this mechanism the members a^{40} are provided, as usual, as are the stop handles a^{45} . The bar a^{65} , however, connected to the stop handles a^{45} , has a link a^{66} pivotally connected thereto and normally inclined forwardly, as shown in Fig. 17, and pivoted at its upper end to the forward end of bar a^{40} . It will be seen that when stop a^{45} is pulled outwardly the inner end of bar a^{40} will be depressed and one of the pins a^{38} depressed.

Operation.

When the organ is played, the upper and lower keyboards will be operated in the usual manner to play the desired notes. It is necessary, of course, in order for the organ to produce tones, that the air under pressure pass through the reed cells. The air is furnished from the air chamber f^1 . The air in this chamber is kept under constant pressure by the springs f^5 and, as described, if the pressure increases too greatly, the valve f^6 will be opened so that the pressure will be relieved. The springs f^5 move the wall f^2 of the bellows and, as stated, maintains a substantially constant pressure on the air. The air is supplied to reservoir f^1 by any supply device, such as the bellows f^9 shown and described and this air supplying device or bellows may be operated by any suitable means, such as the oscillating bar f^{14} , described. When this bar is operated, either by hand or a suitable motor, the straps f^{13} are alternately pulled upon and slackened so that air is pumped by bellows f^9 into chamber f^1 . This air passes from said chamber through the openings f^{17} into the vertical conduits 32° at each side of the organ and passes upwardly through these conduits into the chamber 32. As stated, the valves 33 and 38 normally are open and the air passes downwardly through holes 24^a and 24^b into the comparatively large chamber between the rear of cell board a^1 and the sounding board 26. As the various keys c^1 and c^2 on the lower keyboard are depressed, these keys will operate through pins e^8 , levers e^9 , e^{13} and e^{18} , and through link a^{26} to open three aligned valves in the lower three rows of valves a^8 . When a key on the lower keyboard is thus depressed, air can enter six vertically aligned cells a^2 in the lower six rows of cells on the cellboard a^1 . It will, of course, be understood that when links a^{24} or a^{26} are pulled upon, the bars a^{12} will be swung about the

pivots a^{13} and valves a^8 swung outwardly away from the air inlet openings of cells a^2 . This swinging motion being limited by a stop washer a^{20} . It will be seen that by providing the short rods a^{21} and a^{25} that it is only necessary to thread a comparatively small portion of these rods at their ends in order to secure thereon the leather plugs a^{22} . If one continuous rod were used it would be necessary to thread long portions of the rod. The desired tones are produced by opening certain of the valve sections a^{27} by means of the stops a^{45} . It will be seen that when a stop a^{45} is pulled outwardly lever a^{40} is swung and depresses one of the pins a^{38} which depresses one of the crank rods a^{30} and opens one of the valve sections a^{27} . Only the reeds in the cells which are open by the valve sections a^{27} therefore will play when a key is depressed. If the stops a^{45} opening all six of the cells which have their front ends opened by one key were pulled out then the resulting note would be a result of the vibration of six reeds. When a key on the upper keyboard b is depressed it depresses lever b^9 , pin b^{11} , levers b^{13} , b^{16} and b^{19} and the latter lever depresses one of the links a^{24} . This operates the valves a^8 on four vertically aligned cells in the top rows of cells in the cell board a^1 . These cells will, by the reeds therein, produce notes if the valve sections a^{27} have been opened by the appropriate stops. It will be noted that a large air chamber is provided in the rear of the cell board in which air is maintained at uniform pressure. The various holes and passages through which the air passes from chamber f^1 to the chamber in the rear of the cell board also tends to eliminate any tendency of pulsation in the air supply. The plate or board a^{36} and its flange a^{37} prevent formation of objectionable currents or eddies adjacent the top cell a^2 . As the various valves a^8 are opened, therefore, air is supplied through the cells in a uniform manner. The construction of the cells a^2 described gives a tone which is quite soft and free from any metallic character, the tone being like that produced by an organ pipe. A supply of air at uniform pressure also renders it possible to have the organ operated by a blower system, that is, the air is forced therethrough under pressure. This system differs from that now commonly used in reed organs, which use a suction system or a system of producing low pressure on the outlet side of the cell board. It will be noted that the reed a^6 is disposed in the center of the cell and, of course, the largest cross section thereof. It has been found that when air passes through a more or less restricted passage the air pressure is greater at the center of the passage. The reeds are, therefore, most effectively placed in the cells in applicant's construction.

As stated, the reeds are the ordinary metallic commercial reeds, as shown in Fig. 11. These reeds are placed in the cells a^2 so that the vibrating tongue is on the side opposite that which the air enters, the air coming through the reed from the side opposite that carrying the tongue. The reeds are inserted in and frictionally held in the grooves in the cell board a^1 from the front side thereof. When the bars 24 are removed the reeds can be drawn out from board a^1 , as will be clearly seen from Fig. 16. While the organ, preferably, is operated with air under pressure, delivered from the rear of the cell board a^1 , the organ may be operated by suction or by withdrawing the air from the rear of the cell board a^1 , by removing and inverting the reeds in the cells a^2 . As stated, all of the cells and reeds are supplied with the same amount of air under the same pressure, thus producing an even tone at once from each reed. Also, as previously stated, the lips a^{27} at the exit portion of the cells a^2 affect the character of the tone and greatly improve the same, these lips causing somewhat of a whistling effect, producing a pipe tone. When the organ is being played, the register shutters a^{51} are, of course, open by the knee swells, as desired. When the stops controlling the valves 33 and 38 are operated, some of the openings 24^a and 24^b will be closed. This reduces the quantity of air supplied so that a pianissimo effect is produced. It will be seen that valve 33 and the valve 38 at the right of partition 32^a may be operated together or that both valves 38 may be operated together, thus giving a varied pianissimo tone. The springs 52 are provided to give a slight vibration to valves 51 giving a slight tremolo effect. Three degrees of tone, loud, soft and medium, can thus be secured by the provision of valves 33 and 38.

It may be here stated that the treble valve sections a^{27} are made in two sections to reduce the tendency of the valves to warp.

The tone produced by the organ is greatly improved by the sounding board 26. This board is, as stated, contacted only at its edges and has a substantially unbroken and substantially uniform surface so that there is nothing to interfere with its proper vibration. Also, as previously stated, the board can be removed in a moment's time by simply loosening the wing nuts 30.

When the stop controlling the upper vox humana mechanism is operated, the crank rod 59 is operated and links 57^b and 64 pulled upon. Link 57^b opens valve 57 and air under pressure passes from chamber 54 into the casing 55. At the same time, arm 63 is swung by member 60^a so that shaft 60 is revolved and a starting motion given to the turbine 56. The frame 62 is then revolved by the turbine 56 and the air ad-

5 jacent the organ is given pulsations which affect the resulting waves produced by the organ so that a tone is produced simulating in some respects the human voice. By having a side plate on the turbine and the same mounted in a casing, as described, a very efficient structure and operation of the turbine is produced and one which conserves the air used.

10 The notes produced in the cell board e^1 are produced by operation of the pedals e^9 . If an operator is unable to operate the pedals or does not desire to do so, the notes from the cell board e^1 can still be operated 15 from the lower keyboard by means of the pedal coupler. When this is desired, the crank rod e^{39} is operated by means of a stop connected thereto and bar e^{36} and levers e^{34} moved rearwardly to the position shown 20 in Fig. 1. The bar e^{34} is thus raised by the end cam portion e^{35} riding up on the pins e^{32} . This swings the lever up against the lower ends of pins e^{38} . When the keys e^1 and e^2 , which produce notes separated by 25 octaves from the notes produced by the cell board e^1 , are depressed, the pin e^{38} will depress lever e^{34} and the rod e^{32} corresponding to this lever will be depressed. This will act through one of the crank rods e^{26} and 30 appropriate rod e^{43} will be depressed which will depress its pedal e^9 . When one of the pedals e^9 is depressed either through the rod e^{43} or by the foot of the operator, the rod e^7 is raised and two of the valves e^5 will 35 be opened. Air is supplied to the chamber at the rear of the cells e^2 through the chambers in casing f^{18} and through the conduits f^{19} . The reeds in cells e^2 will be operated when the valves e^{16} are open. These valves, 40 as described, are opened by the appropriate stops. It will be understood that the hinged register door ee^2 will be operated by the proper stop so as to always be open when the reeds in cell board e^1 of the organ are 45 played. It will thus be seen that the lower bass notes produced by the reeds in cell board e^1 can be played either by the pedals e^9 or from the lower keyboard.

By the use of the bass coupler described 50 and the treble coupler described, great organ effect can be produced, also by the use of the manual coupler all the effect of the upper keyboard can be secured by the lower manual or keyboard and this is done without 55 in any way affecting the operation or tones produced by the lower keyboard. When the stops controlling bails a^{61} are operated all of valves a^{27} are opened so that all the reed cells controlled by a key are 60 operated and a great organ effect is produced and a large volume of sound is provided.

All parts of the organ are quite accessible and can be readily reached for adjustment,

replacement or repairs without dismantling 65 the organ or separating many parts which are fastened together by screws. The upper keyboard, as previously stated, can be swung up about the hinge b^{24} after frame 24 has been removed. The lower keyboard carried 70 on frame b^{25} can also be swung about hinge c^{22} and the lower frame member c^{23} can be swung about hinge c^{24} . All parts of the keyboards and transport mechanism are thus 75 easily accessible. As stated, the register 80 panels a^{16} can be very quickly removed, thus exposing the front portion of the cell board a . The bars a^4 can be quickly removed by removal of six or eight screws. The sound board 26 can, as stated, be very quickly removed and access thus had to the rear of the cell board a^1 . The leather plugs a^{22} have been found to be very effective in securing and maintaining the desired adjustment on the rods a^{21} and a^{25} . The valves a^8 can also 85 be easily removed from the bars a^{12} and the bars a^{12} can readily be removed from the bars a^{14} by removal of the strips a^{15} .

From the above description it is seen that applicant has provided a very novel, efficient 90 and convenient structure of organ and one which gives greatly improved tones. The organ has been amply demonstrated in actual practice and the structure and operation thereof have been most successful and the 95 merit thereof fully proven.

It will, of course, be understood, that various changes may be made in the form, details, arrangement and proportions of the parts without departing from the scope of 100 applicant's invention, which, generally stated, consists in a device capable of carrying out the objects above set forth, in the novel parts and combinations of parts disclosed and defined in the appended claims. 105

What is claimed is:

1. A reed organ comprising a cell board with cells therein, each having spaced portions with a reed therebetween, one of said portions having an air receiving opening at 110 one side of said board, and the other having another portion extending longitudinally therefrom beyond said reed and having an air discharge opening at the other side of said board.

2. A reed organ comprising a cell board with cells therein, each having superposed portions with a reed therebetween, one portion extending to one side of the board and having an air receiving opening and the other portion having an additional portion aligned therewith and extending longitudinally therefrom beyond said reed to the other side of said board and having an air discharge opening. 115 120

3. A reed organ comprising a cell board with cells therein, each having spaced portions with a reed therebetween, one of said

- portions having an air receiving opening at one side of said board and the other portion having an additional portion extending longitudinally therefrom beyond said reed, 6 said last two portions having their side walls in alinement and said last mentioned portion having an air discharge opening at the other side of said board.
4. A reed organ comprising a cell board 10 having cells extending therethrough, each of which has an intermediate portion, said cell having elongated portions above and below said reed respectively extending longitudinally thereof from said portion and 15 having respectively air inlet and outlet openings and a reed disposed transversely of said portion.
5. A reed organ comprising a cell board having a cell extending therethrough, one 20 side of said cell having surfaces meeting at an angle to form a point in cross section.
6. A reed organ comprising a cell board having a cell extending therethrough, said cell at its exit end having a downwardly extending substantially sharp edged lip having upwardly and inwardly an inclined inner surface.
7. A reed organ comprising a cell board having cells therein, each of which has offset elongated portions opening, respectively, 25 at each side of said board, said portions overlapping and communicating at their overlapping areas and having a reed extending across said areas.
8. A reed organ comprising a cell board having a plurality of spaced vertically alined pairs of cells extending therethrough, a valve 30 for closing the inlet end of each pair of cells, and a common key-operated means for simultaneously opening all of said valves.
9. A reed organ having in combination, a cell board having a plurality of rows of cells therethrough, detachable bars extending 35 along one side of each row, each bar having a plurality of cells therein alining respectively with and forming extensions of the cells in said board, said bars carrying a plurality of elongated valves each co-operating with a plurality of said cells.
10. A reed organ comprising a cell board having pairs of vertically spaced and alined cells extending therethrough, a flat valve engaging said board and closing the air inlet ends of both cells, a pivoted bar carrying said 45 valve, a spring pressing on said bar above its pivot, a bracket secured to said bar below its pivot, and means for depressing said bracket to swing said bar and valve to open said end.
11. A reed organ comprising a cell board 50 having a cell extending therethrough, a valve for closing the air inlet end of said cell movable about a transverse pivot, a projection on said valve, a rod for depressing said projection and swinging said valve, said rod being threaded at one end, and a leather plug threaded on said end.
12. A reed organ comprising a cell board having a plurality of vertically spaced alined cells, a valve for each pair of cells closing the 70 air inlet ends thereof, a bracket projecting from each valve, members connecting said brackets, and means extending downwardly from the lowermost bracket for operating all of said valves. 75
13. A reed organ having in combination, a keyboard, a series of reeds and reed cells controlled by said keys, a series of bass reed cells and reeds, pedals for controlling said bass reeds and cells, and a coupling device 80 for operatively connecting said bass reeds and reed cells to said keyboard whereby said bass reeds and reed cells may be operated from said keyboard.
14. A reed organ having in combination, 85 a lower keyboard having a series of reed cells with reeds disposed therein controlled by said keyboard, an upper keyboard, a series of reed cells having reeds therein controlled by said upper keyboard, and a coupling device for operatively connecting said last mentioned series of reed cells so that they will be operated by said lower keyboard.
15. A reed organ having in combination, 90 a cell board having reed containing cells therein, air inlet valves for said cells, a chamber for air under pressure at one side of said board, and a sounding board at one side of said chamber engaging the walls of 100 said chamber at its edge portions and being unobstructed inside of said edge portions.
16. The structure set forth in claim 15, and a plurality of detachable securing means 105 for said board spaced about its edges, whereby said sounding board may be readily detached and removed.
17. A reed organ having in combination, 110 a cell board having a plurality of rows of cells therethrough, detachable bars extending along one side of each row and carrying a plurality of elongated valves, each co-operating with a plurality of the air exit ends of said cells. 115
18. The structure set forth in claim 17, said valves each having a spring engaging the same substantially midway between its ends to hold the same in closed position.
19. The structure set forth in claim 17, 120 certain of said valves being connected for simultaneous opening, and means for opening said valves.
20. A reed organ having a plurality of 125 rows of reed cells therein, the cells being vertically alined in said rows, valves for closing the ends of said cells, a lower keyboard, each key of which is operatively connected to a plurality of vertically alined valves in a group of said rows, and an upper key- 130

- board, each key of which is operatively connected to a plurality of vertically aligned valves in the remaining rows of cells.
21. A reed organ having in combination, 5 a cell board having a multiplicity of cells extending therethrough, a chamber for air under pressure at one side of said board, a sounding board having an unobstructed surface forming the side of said chamber opposite said cell board.
22. A reed organ having in combination, 10 an upper keyboard, a frame section carrying said keyboard and a portion of the key transport mechanism, said frame section being pivoted at one side about a horizontal pivot whereby said keyboard may be swung upwardly about said pivot to expose the parts therebeneath and to expose its bottom portion.
23. The structure set forth in claim 22, 15 and a pivoted frame section carrying a lower keyboard to which said first mentioned frame section is pivoted, said last named frame section being swingable upwardly.
24. A reed organ having in combination, 20 a lower keyboard, a frame section carrying said keyboard, and a portion of the transport mechanism, said frame section being pivoted at one side about a horizontal pivot whereby the same may be swung upwardly about said pivot to expose the parts therebeneath.
25. A reed organ having in combination, 25 a pivotally mounted frame section carrying a portion of the transport mechanism, and a pair of frame sections pivotally connected to said first mentioned frame section, each carrying a keyboard whereby said frame portion and sections may be swung 30 about their pivot to expose the parts thereof and the parts therebeneath.
26. A reed organ having in combination, 35 a cell board, a chamber containing air under pressure adjacent the same having a plural-
- ity of series of openings therein, valves for 45 respectively controlling said series, and means for operating said valves to control the volume of air passing through said cell board to vary the volume of sound.
27. A reed organ having in combination, 50 a cell board having a multiplicity of reed-containing cells therein, a chamber adjacent said board, and means for maintaining a supply of air under constant pressure in 55 said chamber.
28. A reed organ having in combination, 55 a cell board, a removable register panel at one side thereof comprising a plurality of substantially parallel pivoted shutters, resilient means adjacent the center of each 60 shutter pressing on the adjacent shutter, and means for swinging all of said shutters in unison.
29. A reed organ having in combination, 65 a cell board having a multiplicity of reed-containing cells therein, a vox humana device adjacent said cell board comprising a fan, a turbine having sides and vanes therebetween for turning said fan, a casing for 70 said turbine and a starting means for initially turning said fan.
30. The structure set forth in claim 29, a 75 valve for admitting air into said casing, and means for simultaneously operating said valve and starter means.
31. A reed organ having in combination, 80 a cell board having rows of vertically aligned reed-containing cells therein, the reeds in different rows giving different tones, valves closing the air inlet ends of said cells, a keyboard each key of which opens a plurality of said valves, and valves at the air exit side of said cells each controlling a plurality of valves in one row, and means for opening 85 one or more of said last mentioned valves to produce the desired tone.

In testimony whereof I affix my signature.
ERICK PETERSON.
